LIGHTING FIXTURE

Morris B. Beck, New York, N. Y.

Application January 29, 1932. Serial No. 589,550

1 Claim. (Cl. 240—78)

This invention relates to lighting fixtures.

Generally, this invention is directed to an arrangement whereby a lighting fixture unit assembly, adapted to receive or including a shade, 5 can be substituted for an electric bulb without requiring electrical or any other changes, and coordinately relates to an arrangement whereby a lighting fixture unit, predetermined as to the positional relationship of its luminous elements 10 with reference to the unit, will receive only an electric bulb capable of effectuating this predetermined relationship of the luminous elements.

It is an object of the invention to provide an electrical fixture which, on assembly with an 15 ordinary outlet in the same manner as any other electrical apparatus, retains its own shading means. The invention has particular application to indirect lighting, and may be applied for converting the ordinary lighting outlet, 20 merely by the insertion of a connector into the outlet, into a fixture having all the properties of an indirect lighting fixture.

For the purposes of the invention, an adapter is formed with a part capable of interlocking engagement with the outlet; it also has a portion 25 providing a receptacle for the association and retention of an electrical lamp therewith. As a part of the adapter, there may be arranged, in any suitable manner, support means from which 30 a shade may be suspended and retained in operative relation to the lamp. Provision is made for removability of the shade in this arrangement, although it is not necessarily requisite.

Particular application of the invention arises 35 from the use of an electrical lamp, itself prepared in such manner that no rays may travel from the lamp in a direction toward the shading means. Lighting of this character requires a larger luminous capacity for the light source 40 than in the case of direct lighting. Since the normal tendency would be to provide lamps of ordinary capacities for use in such assemblies, and since such lamps would not properly produce the results desired, there is associated, in con- 45 junction with the lamp receiving portion of the fixture, means for preventing insertion of lamps of less than a certain predetermined luminous capacity. The shade supporting means, for this purpose, is made the agency for carrying out this 50 function. It is arranged to prevent the association with the receptacle, of lamps other than those having predetermined shaping and, therefore, of a predetermined lighting value.

Other objects of this invention will hereinafter 55 be set forth, or will be apparent from the de-

scription and the drawing, in which is illustrated an embodiment of apparatus for carrying out the invention.

The invention, however, is not intended to be restricted to any particular construction, or to any particular application of such construction, or to any specific manner of use, or to any of the various details thereof, herein shown and described, as the same may be modified in various particulars or be applied in many varied relations without departing from the spirit and scope of the claimed invention, the practical embodiment herein illustrated and described merely showing one of the various forms and modifications in which the invention might be embodied.

For the attainment of these objects and of such other objects as may hereinafter appear or be pointed out, I have illustrated an embodiment of my invention in the drawing in which the same reference characters refer to the same parts throughout, and wherein:

Fig. 1 is a view in perspective of an assembly embodying the invention, shown tilted so that the opening for inserting the lamp and its relation to the bottom face of the lamp appears;

Fig. 2 is a vertical sectional view through the construction of Fig. 1, parts being shown in elevation and parts being broken away, to illustrate more clearly the arrangement of the several elements; and

Fig. 3 is a detail sectional view, illustrating a constructional detail of the shade supporting means.

In the assembly shown on the drawing, an adapter 10 has related thereto a shade 12; between them is positioned an electrical lamp 14. Adapter 10 may be of any desired construction, but preferably has formed therewith, or in any manner secured thereto, a connector 16. This connector or elements similar thereto are media by which the unit, as a whole, may be connected with any ordinary lighting outlet. Preferably, for convenience in making connection to standard outlets and also for efficiency in the retention of the parts with relation to such outlet, the connector is screw-threaded.

The particular construction of the elements within the casing 18 of the adapter is of no material import herein. The connections from the connector to socket 20 of receptacle 22 may be formed in any desired manner so that a lamp 14, positioned in the receptacle, will be positively connected to the power source through the outlet into which connector 16 may be inserted. For the reception of the lamp into this

assembly, socket 20 may likewise be threaded for the reception of the standard threaded end 24 of lamp 14.

Carried from the walls of casing 18 and extending downwardly therefrom, in the construction in which lamp 14 extends from receptacle 22, are a plurality of supporting members, in this case taking the form of rods 26. These rods may be secured to the casing in any preferred manner; they are herein disclosed as welded into recesses 28 formed by the pressed-out portions 30 in the lower rim 32 of the casing, provided for that purpose. The rim, as seen in Fig. 3, is formed as a step in the wall of the casing, and determines the upper limit of association for each rod with the adapter.

The rods are extended downwardly and outwardly, to position their ends 34 in laterally spaced relation to the lamp retained by the adapter and also at a predetermined level relative thereto. The ends 34 are formed with upwardly extending nibs 36 which may be sprung into openings 38 provided on shade 12 by offset members 40. These members are secured in any desired manner, as by welding, adjacent the rim 42 of the shade.

The shade itself may be made of any suitable material. Preferably, it is of metal, shaped like a bowl. In one selected form, the bowl has a cut-out 44 formed at its center. The metal at the cut-out may be dished upwardly, as at 46, for ornamental purposes, and also to protect against abrasion the hand of one inserting a lamp 14 into receptacle 22. Ribbing 48 also adds to the ornamental features of the fixture but, together with the dished-up section 46, strengthens the shade so that thin metal of no consequential weight may be used, thus reducing the load on the adapter.

As is noted from this, cut-out 44 permits the association of lamps 14 with receptacle 22 when such may be desired. The size of cut-out 44 is limited predeterminedly so that the bulb 50 of a lamp to be inserted therethrough for assembly with the receptacle must be smaller than the limit set thereby. This is true not only in effecting such association, but also when subsequently the assembly is positioned for use. By this is meant that while it is evident that nibs 36 could be removed from openings 38, and a lamp having a bulb 50 substantially of any dimension, without reference to cut-out 44, then assembled with the receptacle, still if thereafter it be attempted to assemble those nibs in openings 38 for retaining shade 12 in position, bulb 50 would extend downwardly sufficiently to prevent such association, if it were oversize. For this purpose, the dimensioning of rods 26 and the dished-up section 46 must be coordinated for the assembly of bulbs of a predetermined length where a predetermined bulb diameter is desired.

Preferably lamps having the shaping shown in the drawing are used, since, in this type of lamp, the filament 49 is substantially at the center of the spherical body of bulb 50. Its illumination is much more central than that derived from long filament bulbs. These substantially spherical bulb lamps, as is generally well known, are formed with long necks 52 extending from the ends 24 to the spherical bulb part.

It is desired that, in any particular assembly, the amount of lumens produced shall be a certain minimum. Since the size of the bulbs and the length of their necks conform closely to the quantity of lumens produced by any

particular bulb, and are substantially proportionate thereto, rods 26 are shaped to permit association with a particular receptacle of a lamp having the requisite dimensions for emitting the necessary lumens. The rods may be designed substantially L-shape in appearance, extending away from the casing in a line following closely that of the shaping of neck 52. At the juncture of the neck and the bulb, a rounded fillet is provided. Rods 26, conforming thereto, have rounded corners 54 from which extend away substantially horizontal sections 56, terminating in ends 34. In this manner, the shaping of the rods is such that lamps 14, of insufficient capacity, may not be assembled with the adapter, as the rounded corners 54, positioned by the legs 58 of the rods, will prevent access to the receptacle by short neck, low capacity lamps.

Lamps for use in these adapters have a lower section 60 of the bulb 50 coated or otherwise provided with a reflector 62 adapted to redirect light rays back into the bulb. Light rays, tending toward the cut-out 44, will thereby be directed upwardly toward the ceiling or like member, from which they may be diffused over the surface and parts to be illuminated. The reflector 62 extends above the level of the filament 49 in a preferred construction, thus preventing any direct downward rays from passing from the lamp. Also, this position of the filament with regard to the rim 42 of the shade, whereby all rays passing from the lamp must first pass away from the point to be illuminated, is assured by the formation of rods 26, previously set forth.

In order to prevent the production of shadows, section 64 of the bulb and the neck 52 are formed of frosted, rather than transparent, glass for diffusing rays issuing at these points. Shadows of rods 26 and of the casing on the ceiling or other parts with relation to which the adapter is assembled are, by this means, eliminated. The inner face 66 of the shade preferably is finished in a dull, light absorbing color to prevent reflection from its surface.

It will thus be observed that I have attained one of the main functions of my invention in that I have provided an inexpensive and simple indirect lighting unit assembly which can be substituted for a bulb in the same manner as one bulb can be substituted for another, and which, merely by such substitution, will give the results of a complete and efficiently operating, indirect lighting assembly without requiring the work of an electrician or any wiring or other mechanical or electrical changes. Further, I have assured that the efficiency of the assembly shall not be marred by inexpert or careless arrangement of improper lighting elements therewith.

Many other changes could be effected in the particular apparatus designed, and in the methods of operation set forth, and in the specific details thereof, without substantially departing from the invention intended to be defined in the claim, the specific description hereinabove being merely to illustrate an operative embodiment carrying out the spirit of the invention.

Having thus described my invention and illustrated its use, what I claim as new and desire to secure by Letters Patent is—

An indirect lighting unit comprising in combination a connector member adapted for association with a standard lamp outlet and provided with means suitable for receiving an illuminating bulb, an illuminating bulb positioned within

said socket, said bulb comprising a substantially spherical portion joined to a relatively narrow neck portion carrying a base suitable for insertion into said receiving means, a part of the 5 spherical surface of said bulb being provided with a reflecting coating preventing outward passage of the light rays and redirecting them, a bowl-shaped reflector fixedly positioned in relation to said connector member by a plurality 10 of supporting members springing from the connector and running along the neck portion of the bulb and substantially up to the beginning of the spherical portion of the bulb, and from that point directed outwardly in a substantially horizontal direction and with their outer ends terminating at and fixedly related to the bowl-shaped reflector, and a central opening in said reflector large enough to permit passage therethrough of the spherical portion of the bulb, said reflector being held in such relation to said bulb that the coated end of the spherical bulb portion is located within the central portion of the reflector. 80 85
